UNITED STATES PATENT OFFICE.

GEORGE ALPHA MILHOLLAND, OF PITTSBURG, PENNSYLVANIA.

SMOKE-BELL.

No. 896,564.

Specification of Letters Patent.

Patented Aug. 18, 1908.

Application filed April 20, 1908. Serial No. 428,063.

To all whom it may concern:

Be it known that I, GEORGE ALPHA MILHOLLAND, a citizen of the United States of America, residing at Pittsburg, in the county 5 of Allegheny and State of Pennsylvania, have invented certain new and useful Improvements in Smoke-Bells, of which the following is a specification, reference being had therein to the accompanying drawing.

10 This invention relates to a smoke bell and the primary object of my invention is to provide a novel bell for causing a diffusion of the heat units emitted by a gas light.

A further object of my invention is to 15 provide a simple durable and inexpensive smoke bell that can be easily suspended over a light or lamp, either to cause a diffusion of the heated air above the light or lamp, or to protect a ceiling from the lamp or light.

20 With the above and other objects in view which will readily appear as the invention is better understood, the same consists in the novel construction, combination and arrangement of parts to be presently described and 25 then specifically pointed out in the appended claims.

In the drawings, Figure 1 is an elevation of my smoke bell suspended above the light or lamp of a chandelier. Fig. 2 is a cross 30 sectional view of a smoke bell partly in elevation. Fig. 3 is a horizontal sectional view of a smoke bell partly broken away.

In the accompanying drawings, 1 designates a metallic plate or disk to which is 35 secured by rivets 2 a hook 3, constituting a hanger whereby the bell can be suspended from a suitable support above a light or lamp 4. The rivets 2 also serve to hold a U shaped arm 5, in engagement with the 40 plate, said arm being provided with two diametrically opposed screws 6 and 7, the screw 6 extending through the plate or disk 1 and having a suitable bearing 8 for the shaft 9 of a bladed wheel 10, the opposite 45 end of said shaft resting in the end of the screw 7, which extends through the arm 5. The screws 6 and 7 upon the confronting sides of the arm 5 are provided with jam nuts 11 having levers 12, whereby after the 50 screws are adjusted they can be locked in a fixed position. The bladed wheel 10 is provided with a central spider or reinforcement 13 suitably secured to the shaft 9. The blades of the wheel 10 are formed at such an

angle that the heat emitted by the light or 55 lamp 4 will be scattered about the compartment in which the light or lamp is located.

The bearings in the ends of the screws 6 and 7 can be jewel or any type of bearing that will reduce the friction of a shaft to a 60 minimum.

The smoke bell in its entirety is constructed of light and durable material that can be finished to harmonize with the gas or lamp fixture in connection with which it 65 is used.

Having now described my invention what I claim as new, is:—

1. A smoke bell comprising a plate or disk, a hook, a U-shaped arm, rivets securing said 70 hook and said arm to said disk or plate, screws carried by the confronting sides of said arm, a shaft revolubly mounted between said screws, a bladed wheel, a spider or reinforcement carried by said wheel and fixed 75 upon said shaft, and jam nuts mounted upon said screws.

2. A smoke bell comprising a plate or disk, a hook, a U-shaped arm, screws adjustably mounted in said arm, a shaft revolubly 80 mounted between said screws, a bladed wheel fixed upon said shaft, jam nuts carried by said screws, and means for securing said arm and said hook to said plate or disk.

3. A smoke bell comprising a plate or disk, 85 a hook attached thereto, an arm attached thereto, screws carried by said arm, a shaft journaled between said screws, a bladed wheel fixed upon said shaft, and means for fixing said screws in said arm. 90

4. A smoke bell comprising a plate or disk, a hanger secured thereto, a U-shaped arm carried by said plate, oppositely disposed screws mounted in said arm, a shaft revolubly mounted between said screws, and a 95 bladed wheel carried by said shaft.

5. A smoke bell comprising a plate or disk, a hanger secured thereto, a U-shaped arm carried by said plate, oppositely disposed bearings carried by said arm, and a bladed 100 wheel revolubly mounted between said bearings.

In testimony whereof I affix my signature in the presence of two witnesses.

GEORGE ALPHA MILHOLLAND.

Witnesses:
